UNITED STATES PATENT OFFICE

WILBUR N. SQUIRES, OF JOPLIN, MISSOURI, ASSIGNOR TO HYDRAULIC DEEP WELL PUMP COMPANY, OF JOPLIN, MISSOURI, A CORPORATION OF MISSOURI

HYDRAULIC PUMP

Application filed May 16, 1928. Serial No. 278,146.

The present invention relates to pumps of the class disclosed in my copending applications, Serial No. 159,896, filed January 8th, 1927, and Serial No. 275,404, filed May 5, 1928, which are operated by a pulsator or jack at the head of the well through hydraulic transmission.

In working pumps of the type shown in the first above named application, two columns of liquid are employed to drive a movable piston or plunger system back and forth to make the intake and discharge strokes of the pump by pressure applied alternately to the columns.

Whereas the specific form of pump which will be shown herein relates more particularly to the system wherein pressure is applied alternately to the two columns, it is to be understood that certain features of the present pump are applicable to the type shown in the second named application wherein pulsations of pressure are applied only to one of the columns and static pressure is permitted to make the return stroke of the pump.

Where pressure is applied alternately to the two columns and where, as has been the practice and is disclosed in my prior application, the two columns are concentric, it is to be observed that the inner column, which employs the pipe of smaller diameter, is adapted to sustain pressures much higher than the outer column which is contained within the pipe of larger diameter. The column contained within the inner pipe has a greater ratio of wall thickness to diameter than the pipe around the outer column, and in addition the inner pipe is to some extent relieved of excessive stress because of the hydrostatic pressure of the outer column. As a result the inner pipe can sustain pressures much greater than are permissible in the outer column, and furthermore the stretch or yield of the inner pipe is much less than in the outer column for equal pressures.

When it is necessary for a pump of this character to work in a well several thousand feet deep, the pressures which are encountered become very high. Also due to the reversing of the columns of liquid for each

stroke, the stresses which must be sustained by the various parts run to a high value. It is, therefore, desirable to operate on a theory or mode of operation which will impose a minimum pressure on the outer column even though this must be done at some increase of pressure on the inner column.

The principal object of the present invention is to provide a structure which will embody mechanism for permitting the pump to be operated on a minimum pressure in the outer column and yet which provides a simple mechanical structure.

The space in which a pump of this character must be disposed is greatly limited in diameter, although there is no particular limitation on endwise length.

According to my invention I provide an additional or static plunger which is available on the upstroke of the pumping plunger, which upstroke in the specific embodiment shown is made by applying pressure to the outer column. Obviously the direction of stroke is immaterial. The displacing stroke is made by pressure applied to the inner column, and the intake stroke is made by pressure applied to the outer column. That is to say, the work done by the stroke of the inner column corresponds to the discharge of liquids by the pump to the head of the well, whereas the stroke made by the outer column corresponds to the suction stroke for taking liquid into the pump from the well.

The desired result of decreasing the stresses upon the mechanism is secured by the use of the so-called static plunger. The pump of my invention, in addition to providing the static plunger, provides certain simplified mechanical structures and assemblies which are highly desirable in pumps of this type. For example, the cylinders are formed as removable liners which may readily be replaced in the field without difficulty, and which facilitate assembly in the manufacture of the device. The parts are readily interchangeable, and without great change in the manufacture the pump may be constructed in accordance with the disclosure of my second named copending application to make up

a pump which operates on the return stroke by static pressure only.

Now in order to acquaint those skilled in the art with the manner of constructing and operating a device embodying my invention, I shall describe in connection with the accompanying drawings a specific embodiment of the same. In the drawings a single embodiment is shown, and the top of the pump is shown in Fig. 1A, the intermediate section in Fig. 1B and the bottom section in Fig. 1C. These three figures are supposed to be assembled end to end to present a vertical longitudinal section through the pump of my invention.

Fig. 2 is a cross sectional view taken on the line 2—2 of Fig. 1A.

Fig. 3 is a cross sectional view taken on the line 3—3 of Fig. 1A.

Fig. 4 is a cross sectional view taken on the line 4—4 of Fig. 1B.

Fig. 5 is a cross sectional view taken on the line 5—5 of Fig. 1C; and

Fig. 6 is a fragmentary diagrammatic sketch illustrating the principle of operation of my pump.

I provide an inner string of pipe 3 for defining an inner column of liquid 1 and an outer string of pipe 4 for defining an outer column of liquid 2. The string of pipe 3 is connected through a threaded coupling 5 with a suitable slip joint 6 which comprises telescopic parts, the first of which includes a tubular member 7 having a shoulder 8 and a depending cylindrical skirt or flange 9 closely embracing the neck 10 of the flange coupling member 11, the flange 12 of which is embraced between the head 13 of the power cylinder 14, and a shoulder 15 formed on an offset coupling member 16.

The string of pipe 4 is connected through a reducer coupling 17 to the offset coupling 16, and the lower end of the offset coupling 16 is connected by a threaded portion to the sleeve 18 lying outside of the cylinder 14. The sleeve 18 has a shoulder at 19, and the head of the cylinder 14 likewise has a shoulder at 21. The upper end or head 13 of the cylinder 14 abuts against the bottom of the flange 12 of the telescopic coupling member 11, and by the threaded assembly of the offset coupling 16 and the sleeve 18 these parts are held firmly together.

The inner string of pipe 3 may be raised to separate the telescopic coupling 6, and thereby to open up the upper ends of the passageways 22 which lead down through the flange and then radially out through the side walls.

The head of the cylinder 14 has short longitudinally extending flanges or lands 23, as may be seen from Fig. 2, defining between them longitudinal passageways 24. The flange 12 of the telescopic coupling member 11 likewise has passageways therethrough

registering with the passageways 24 so that the outer column 2 communicates with the space 25 surrounding the cylinder 14.

The sleeve 18, which is preferably made of a length of seamless steel tubing, is connected by a threaded coupling 26 to another sleeve member 27 like the sleeve member 18. The sleeve 27 defines the crosshead chamber 28. Between the lower end of the sleeve 18 and a shoulder 29 on the sleeve member 27 there is clamped a guiding spider 30 which guides or radially supports the lower end of the cylinder liner 14, this liner being provided with a suitable ring cut therein to fit inside the spider.

The spider is thus set radially inwardly to provide room for the formation of passageways therethrough to provide communication between the space 25 and the crosshead chamber 28.

A hollow tubular plunger 31, herein termed the power plunger or power piston, works in the bore 32 of the cylinder 14. Preferably a very close fit is provided, as by grinding the cooperating cylindrical surfaces to a close fit. The lower end of the tubular plunger 34 is closed by a coupling 33 which is threaded over the open end of the plunger. The coupling member 33 thereby forms a cap for the lower end of the tubular plunger 31, and a stud 34 which forms the lower extension of the same, is threaded into the crosshead 35. A pair of rods 36, 36 are connected to the crosshead 35 and thereby to the power plunger 31, and these rods extend on down through the remainder of the crosshead chamber 28 past the static cylinder 38 and connects to another crosshead member 39 to which the pumping plunger 40 is connected.

Obviously instead of two rods 36, 36 a greater number may be employed, as for example three or four, the purpose of these rods being to transmit the effort of one of the plungers to the others. The crosshead 39 has a recess 41, into which is threaded the lower end of the hollow tubular static plunger 42, which plays in the bore 43 of the static cylinder 38. The static cylinder 38 has a head 44 at the upper end, and similarly a head 45 at the lower end, and this static cylinder 38 is pressed into the lower end of the sleeve section 27.

The head 44 has suitable wings or lands permitting the rods 36, 36 to move freely therethrough, and likewise to provide free communication for the passage of liquid from the discharge valve chamber 46 up to the crosshead chamber, thence through the space 25, and up to the column 2.

The lands 47, 47 on the sides of the static cylinder 38 extend throughout the full length of the same, whereas the lands 48 and 49 are formed only at the heads 44 and 45.

The plunger 42, like the plunger 31, is

ground to a close fit in the bore 43 of the static cylinder 38.

The bore of the static cylinder communicates by way of a passageway 50 with the outside of the sleeve member 27 through a small check valve to permit any fluid which may leak into the cylinder 38 to be expelled but to prevent the drawing of any liquid into said cylinder. This passageway 50 extends 10 through one of the lands 47 in the head member 44.

The hollow pumping plunger 40 fits closely within the cylinder 52, which is constructed substantially like the cylinder 14. The cylinder 52 has a sharp conical shoulder 53 at its upper end, and adjacent said shoulder is steadied by means of the spider 54 which is shown in cross section in Fig. 5, this spider being constructed like the spider 30 shown in Fig. 20 1A and being held at its outer periphery between the lower end of the sleeve 55 and another threaded sleeve 56 which surround the pumping cylinder 52. The head 58 of the cylinder 52 has a shoulder 59 which is engaged by a shoulder 60 on the inner wall of the sleeve 56, and a flanged coupling member 61 has a shoulder 62 bearing against the lower edge of the head 58.

The flanged coupling 61 has an inwardly extending flange 63 which embraces the cylindrical wall 64 of an intake valve housing, said housing having an outwardly extending flange 65 which is engaged by the flange 63 of the coupling member 61. A space 66 between the sleeve 56 and the cylinder wall 52 defines a sediment chamber, into which scale, sand and the like, which is generally termed sediment, may gravitate and thus be diverted from the working surfaces.

The housing 64 encloses a cage 67 for the inlet check valve 68, a suitable removable seat 69 being provided. A drop pipe 70 is connected to the housing 64, and a suitable screen 71 is supported thereupon. An intake pipe 45 72 communicates with intake check valve 68 to conduct oil or other liquids thereto upon the suction stroke of the plunger 40.

The plunger 40 is connected by a cage member 73 to the crosshead 39, the cage 73 having 50 a stud 74 which is threaded into the crosshead 39. A discharge check valve 75 is mounted in the cage, and between the cage and the upper end of the plunger a removable valve seat 76 is provided.

It will be observed that the static cylinder 38 being pressed into the tubing section or sleeve 27, is the only part which is not 55 freely rotatable with respect to the piston system. That is because the rods 36, 36 are guided through openings in the heads of the cylinder 38, and hence the movable piston system must rotate with the sleeve 27 or remain stationary therewith when the sleeve sections are threaded together.

In the specific embodiment herein shown,

the power piston 31 has a diameter of 3 inches, the static piston has a diameter of 2 $\frac{1}{8}$ inches and the pumping plunger has a diameter of 2 inches. The outside diameter of the pump is 6 inches. These dimensions are given by 70 way of example and not as limiting.

It will be observed that I have made the power plunger 31 of a considerably larger diameter than the pumping plunger, and the static plunger 42 is of an intermediate diameter. 75

The operation of the pump shown herein is as follows: Assuming that the pipe strings 3 and 4 are connected to the two cylinders of a jack or pulsator, or to opposite ends of the same cylinder of a jack or pulsator, so that liquid is displaced under pressure alternately in the columns 1 and 2. Assume now that pressure is applied to the column 1 and released on the column 2. Thereupon 80 the pressure of the liquid is exerted on the full cross section of the power plunger 31, forcing down the static plunger 42 and the pumping plunger 40. While no liquid is forced out of the pump by the downward 85 movement of the pumping plunger 40, liquid is transferred from the inside of the plunger to the outside, that is, into the crosshead chamber 46, which serves as a discharge check 90 valve chamber. However, the downward 95 motion of the plungers 31 and 42 forces liquid up through the column 2 and causes a discharge of the same at the head of the well. The downward motion of the plunger 42 is opposed only by the displacement pressure on the outside and by suction on the inside. Upon release of pressure on the column 1 and the application of pressure on the column 2, the reverse or upper stroke 100 is made.

Since hydrostatic pressure is applied to both plungers 31 and 42 to force them upwardly, and to 40 to force it downwardly, the resultant effect will be the algebraic sum of these actions, and since the pumping plunger 40 is smaller in diameter than the static plunger 42, there will be effective an upward pressure from the algebraic sum of the pressures on the pumping plunger 40 and the static plunger 42, and in addition to that there will be the full value of pressure upon the cross section of the power plunger 41. Therefore the piston moves upwardly. Since the suction created by raising the plunger 40 is relatively small as compared with the pressures required to raise liquid from the well to the head of the well, it can be seen that the return or suction stroke is made quite easily, that is, without requiring the exertion of very much pressure in the column 2. Also to whatever extent suction prevails in the static cylinder this tends to assist in raising the plunger system. 115

It will be observed that the upper plunger 31, which is the power plunger, is hollow and 120

has a sharp conical upper edge leading into the interior of the same, thereby to dislodge sediment from the bore 32 and divert it into the sediment chamber 78 which is formed 5 on the inside of the power plunger 31.

Similarly if any sediment should find its way into the static cylinder 38, the same will gravitate into the sediment chamber 79 formed in the plunger 42. The plunger likewise has at its upper end an inwardly tapered shoulder to scrape any sediment from the walls and divert it into the sediment chamber 79. Any sediment which might stick to the outside of the power plunger 31 when 10 the same is extended from the power cylinder 14 is scraped off by the sharp conical lower edge of said cylinder 14, and the same then tends to drop by gravity downwardly and may lodge in the sediment pocket 66 15 formed between the lower or pumping cylinder 52 and its side wall 56.

It will be apparent from the above description that the pump of my invention may omit the static cylinder and its plunger where the 20 required pressure for making the return stroke is not too great, said pressure acting upon the difference in area between the power plunger and the pumping plunger, to make the up-stroke.

30 I do not intend to be limited to the details shown or described except as hereafter recited in the claims.

It will be observed also that while I have shown a hollow tubular pumping plunger 35 carrying its own discharge check valve and this is the preferred construction, it is not essential that the working element of the pump be hollow, that is, contain the discharge passageway, as obviously the hollow feature 40 may be dispensed with and the pump cylinder constructed in any preferred manner known in the art.

Certain of the details of construction are new and may be employed independently of 45 other features or combinations of the pump, and I am, therefore, laying claim to the same.

I claim:

1. In a device of the class described, the combination of a differential hydraulic motor, a hydraulic pump having a piston member and a valved discharge passageway, said differential motor comprising a power cylinder and a static cylinder, the power cylinder being open at both ends and the static 50 cylinder being open at one end only, pistons for said cylinders connected together and to said pump piston, and means defining a pair of hydraulic columns, one of the columns 55 communicating only with one end of the power cylinder, the other column communicating with the opposite end of the power cylinder, with the open end of the static cylinder and with the discharge passageway of the pump.

2. In a pump of the type wherein liquid is 60 pumped by reciprocating two liquid pres-

sure columns and imparting an upward drift to at least one of the columns, the combination of an outer cylindrical shell comprising a plurality of sections and defining at least a portion of one of the columns, a removable power cylinder mounted in one of the sections and communicating with one of said columns, a removable pumping cylinder mounted in another one of the sections and communicating under predetermined conditions with the other column, and a static cylinder fixedly mounted in an intermediate section, said cylinders being held in alignment, pistons for the cylinders, and connections between the pistons to cause them to move in unison. 70

3. In combination, an outer sectional cylindrical casing defining a portion of a discharge column, a string of tubing connected to the same at one end and an intake check valve connected thereto at the other end, a removable power cylinder liner mounted in a section adjacent the attachment of the string of tubing and communicating with the hereinafter mentioned power column, a removable pump cylinder liner mounted in the section adjacent the intake check valve and communicating under predetermined conditions with the discharge column, a static cylinder mounted in an intermediate section of the casing and being fixed in position therein, a string of tubing connected to the adjacent end of the power cylinder and lying inside the first string of tubing and defining a power column, a power plunger in the power cylinder, a pumping plunger in the pumping cylinder, and a plunger in the static cylinder, and connections between said plungers including rods lying radially outside the static cylinder. 90

4. In a device of the class described, an outer cylindrical casing built up of a plurality of sections and defining a portion of a discharge column, a removable power cylinder liner mounted in the uppermost section, a string of tubing communicating only with the upper end of the cylinder liner and defining a power column, a second string of tubing surrounding the first string of tubing and connected to the upper end of the casing, a removable pump cylinder liner mounted in the lower end of the casing and closing off the lower end thereof, an intake check valve housing communicating with the lower end of the pump cylinder liner, a tubular pumping plunger carrying a discharge check valve and being mounted in the pumping cylinder liner, and a power plunger mounted in the power cylinder and connected to the pumping plunger, said discharge check valve establishing communication between the pumping cylinder and the discharge column. 100

5. In a pump of the class described, the combination of an outer tubular shell section, a removable cylinder liner therein, said shell being counterbored to provide a shoulder, the cylinder liner having at one end an 110

outwardly projecting flange having a shoulder cooperating with said shoulder in the casing and fitting in the counterbore, said cylinder liner having a reduced neck at the opposite end and a spider braced against the wall of the casing and embracing the said neck.

5. In combination, a tubular casing section threaded at each end and having a counterbore at one end, a removable cylinder liner having a flange seated in the counterbore and having a reduced neck at the opposite end, a flanged tubular member adjacent the flanged end of the cylinder liner, a threaded coupling member holding said flanged tubular member endwise in alinement with the cylinder liner, a circular spider embracing the neck at the end of the liner and bearing radially against the inner walls of the casing section, and an adjacent casing section threaded to the first casing section clamping the spider in fixed position.

6. In combination, a pump of the class described, the combination of a tubular casing section having a counterbore at one end, said casing section being threaded at each end, a cylinder liner having a flange seated in said counterbore, a flanged tubular member lying endwise in alinement with the flanged end of the cylinder liner, the flange of the cylinder liner being slotted to provide longitudinal passageways, a string of tubing connected to the tubular member, a threaded coupling member threaded into one end of the casing section 25 and holding the flange of the tubular member in engagement with the flange of the cylinder liner, the flange of the tubular member being slotted to provide passageways in alinement with the passageways through the flange of the liner and a second string of tubing surrounding the first string of tubing and connected to said coupling member and communicating through said aligned passageways with the remote end of the cylinder liner.

7. In combination, a lower tubular casing section threaded at each end and having a counterbore at its lower end, a pump cylinder liner having a flange lying within said counterbore, an intake valve housing having a flange lying against the flange of the liner, and a threaded coupling member embracing the flange of the housing and threaded upon the lower end of the casing section and holding the housing, the liner and the casing section in assembly.

8. In combination, a tubular casing section, a cylinder member closely fitting and held within said casing section, said cylinder member having a bore opening downwardly and closed at its upper end, a plurality of longitudinal guides extending longitudinally of the cylinder member and lying within the casing section, a cylindrical piston member lying within the bore of the cylinder

member, a crosshead connected to the lower end of the piston member, and rods disposed in said guides and connected to said crosshead.

10. In combination, a pump comprising a sectional tubular casing, an outer string of tubing connected to the casing at one end, an intake valve housing connected to the casing at the other end, a removable power cylinder liner mounted in the casing at the upper end, an inner string of tubing communicating with the upper end of the power cylinder liner, a piston in said cylinder liner, a pumping cylinder liner removably mounted in the lower end of the casing and having its lower end opening into the intake valve housing, a tubular pumping plunger mounted in said latter cylinder liner carrying a discharge check valve, a crosshead connected to the pumping plunger, a crosshead connected to the power plunger, and rods connecting said crossheads.

11. In combination, a tubular sectional casing defining a discharge column, an outer string of tubing connected to the upper end of said casing, an intake check valve housing connected to the lower end of the casing, a removable pumping cylinder liner having a bore communicating with the intake check valve housing and closing off the lower end of the casing, a pumping plunger carrying a discharge check valve working in the bore of the pumping cylinder liner and establishing communication between the pumping cylinder and the discharge column, a power cylinder liner mounted in the upper end of the casing, an inner string of tubing communicating only with the upper end of the power cylinder liner and defining a power column, the power cylinder liner having passageways between itself and the casing, a static cylinder mounted in a section intermediate the aforesaid sections of the casing, a power plunger in the power cylinder liner, a static plunger in the static cylinder, said static plunger being acted upon by the discharge column, and connecting rods extending along the sides of the static cylinder for connecting all of said plungers together.

12. In a pump of the type wherein liquid is pumped by reciprocating two liquid pressure columns and imparting an upward drift to at least one of the columns, a tubular sectional casing comprising an uppermost section, a power cylinder liner mounted in said section and readily removable therefrom and communicating with one of said columns, a static cylinder section having a static cylinder permanently mounted in the lower end thereof and defining a crosshead chamber in its upper end, a crosshead chamber section of the casing being connected to the lower end of the static cylinder section and a pumping cylinder section at the lower end, and a pumping cylinder liner removably mounted

in the lower end of the same and communicating under predetermined conditions with the other column.

13. In a pump of the class described, the combination of a sectional tubular casing comprising four sections threaded together, an outer string of tubing connected to the upper end of the first section, a power cylinder removably mounted in the upper end of said first section, a static cylinder fixedly mounted in the lower end of the second section and a pumping cylinder removably mounted in the fourth section and communicating with the hereinafter mentioned discharge column under predetermined conditions, an intake valve communicating with the lower end of the pumping cylinder, plungers for said cylinders, connections for the plungers, and an inner string of tubing communicating only with the upper end of the power cylinder and defining a power column, the space between the inner and outer string of tubing comprising a discharge column, the pump cylinder communicating with the discharge column and the static plunger being acted upon by said discharge column.

14. In a pump, an outer sectional shell, a cylinder liner spaced from the wall of the shell and having a radial extension at one end, said radial extension being clamped between sections of the shell, and a spider lying between the other end of the liner and the walls of the shell, said radial extension and said spider having longitudinal passageways communicating with the space between the liner and the shell.

15. In a pump of the type wherein liquid is pumped by reciprocating two liquid pressure columns and imparting an upward drift to at least one of the columns, an outer shell defining one of the columns, a power cylinder liner mounted in the shell and constituting the lower terminal of the other of said columns, said liner opening into the shell at its lower end only, a static cylinder mounted in the central part of the shell and having its upper end closed off from and its lower end opening into the shell, a pumping cylinder in the lower end of the shell having its upper end opening into the shell and its lower end communicating with the outside of the shell, said communication including an intake check valve, a tubular pumping plunger in the last named cylinder discharging into the shell, a piston for the static cylinder and a piston for the power cylinder, said pistons being coupled together and connected to said plunger.

In witness whereof I hereunto subscribe
60 my name this 12th day of May, 1928.
WILBUR N. SQUIRES.
